United States Patent Office.

A. E. DUPAS, OF NEW ORLEANS, LOUISIANA.

Letters Patent No. 93,689, dated August 17, 1869.

IMPROVEMENT IN ELECTRO-MAGNETIC ENGINES.

The Schedule referred to in these Letters Patent and making part of the same.

To all whom it may concern:

Be it known that I, A. E. DUPAS, of Paris, France, but now residing in the city of New Orleans, State of Louisiana, have invented a certain new, useful, and improved Electro-Magnetic Machine, and mode of connecting the same as a motor to sewing-machines; and I do hereby declare the following to be a clear, full, and exact description of the same, reference being had to the annexed drawings, making a part of this specification, in which—

Figure 1 is a side elevation, and

Figure 2 an end view of said improvement.

The especial object of my invention is to create a motor for sewing-machines, which will operate them more economically than can be done by any other motive-power, but my invention can, with equal advantage, be applied to a variety of other economic uses, that need not herein be specified, wherein a moderate degree of power only is required to be brought into action and considerations of economy have any weight.

The nature of my invention will be best indicated by a description of its construction and mode of operation, which will at once disclose the same, and show that my combination and arrangement of the parts of which my machine is composed dispense entirely with the heavy, rigid, and cumbrous members heretofore considered indispensable in electro-magnetic machines, and that hence an increased quantum of power is developed for transmission and useful application to whatever machine it may be employed to operate, whether such transmission be in a direct and positive manner or through the agency of intermediate gearing.

But this description can be better given, and my invention be more readily and quickly understood, by referring to the drawings, on which the same letters denote the same parts at both the figures.

Upon a proper pedestal, platform, or table A, is mounted and permanently secured a tri-pole electro-magnet B B' B'', the central pole B', of which, is provided with a curved top, while the side-poles B and B'' are provided with corresponding curved but more extended heads D D, which curved extended heads, it will be observed, subserve the purpose of guide-ways for the hollow cylindrical armature C, which is placed on top of the same, and between which and the said extended heads of the exterior poles B and B'' there must be a continual and perfect contact, in order that the magnetism developed or induced by the battery (which latter is not shown on the drawing) may be utilized and applied to the best advantage.

This cylindrical armature is made hollow, to reduce its weight and friction, as well as to facilitate its attraction by the central pole B' of the magnet, by con-

fining the whole inducing-power of the magnet to its surface.

E E is a vibrating or oscillating frame, (the points of articulation being at e and e', at or near the base of the magnet, which said frame straddles,) in which the armature C is sustained on a central axis, F, as shown transversely across the heads D D, in such a manner as to keep the said armature in close and perfect contact with the said heads.

This vibrating frame E E constitutes the mechanical instrumentality, through the agency of which motion is communicated to the fly-wheel G by means of the connecting pitman H and the crank J, and by which I am enabled to dispense with, as wholly unnecessary, the heavy and cumbrous frame-work that is employed for the like purpose in all existing electro-magnetic machines of which I have any knowledge.

K is a double eccentric, or cam, that is placed on the axis of the fly-wheel G, to operate the spring-commutators L and M, and through them to fulfil the function of closing the circuit at the beginning of each stroke, and breaking said circuit when the armature is at about the centre of the heads D D, or in a position that is over the perpendicular axis of the magnet, allowing the armature and oscillating frame to complete the stroke by its momentum in a manner analogous to the cut-off in a steam-engine.

The armature C and vibrating frame E E are thus caused to oscillate to and fro and transmit a rotary motion to the crank J and fly-wheel G, through the pitman H.

To make a direct application of my electro-magnetic machine as a motor to operate a sewing-machine, nothing further is necessary than to extend the axis O' of the fly-wheel G, as shown at o, fig. 2, first providing a lateral supporting-arm, R, having a vertical standard, S, in which to mount a proper journal-box, and a pendent arm, T, having projecting bents u u, to serve as guide-ways for a needle-bar, V, that is operated by a crank-pin, i, that takes into a horizontally elongated slot 2, (see fig. 1,) at the upper extremity of said bar, or any suitable direct connection with the needle-arm of any ordinary sewing-machine.

To start and to stop the machine, I employ a projecting conductor or head, m, a non-conducting head, n, with an ordinary switch or strip of metal, N, which is provided with an ivory or other suitable non-conducting knob or handle, n'.

These, after proper insulation from each other, when the platform A is of metal, are secured upon the platform, as shown upon the drawings, so that when the machine is to be put in operation, the operator will only have to push the switch N by the handle n', upon the head m, to close the circuit of the battery, while, to stop the machine, the switch will have to be

pushed upon the non-conducting head n , to break the circuit of the battery.

In order to regulate the speed of the machine, without breaking the circuit of the battery, I employ a friction-arm, W , in connection with a treadle-lever, z . A depression of said treadle-lever brings the friction-arm, at its upper end, which is provided with a curved brake, in contact with the axis O' of the fly-wheel, and by tractive power effects the object.

A suitable battery is connected with the machine in any usual manner by conducting-wires, and it is ready for use.

I have demonstrated, by actual experiment, that my machine will drive a sewing-machine for twelve hours continuously, at a cost of less than forty cents.

Having thus described my invention,

What I claim, and desire to secure by Letters Patent, is—

1. The tri-pole magnet having its central pole B formed with a curved top, while the side poles $B'B''$ are provided with corresponding curved but more extended heads $D D$, in the manner and for the purpose as described.

2. The rotating hollow cylindrical armature C , provided with a central axis, F , or its equivalent, for the purposes herein described.

3. The combination of the tri-pole magnet $B B' B''$, with the oscillating frame $E E$, and the rotating hollow cylindrical armature C , as herein stated, to operate as described.

4. The above combination, in combination with pitman H , crank J , fly-wheel G , double eccentric K , and commutators L and M , when these parts are constructed, arranged, and operate substantially as set forth.

5. The electro-magnetic machine, as herein described, as a whole, in combination with a sewing-machine, when the two are united in the manner and by the means substantially as herein described, and the motion of the needle is controlled by means of a friction-arm or brake, W , operated by a treadle-lever, z , as set forth.

A. E. DUPAS.
